UNITED STATES PATENT OFFICE.

CLINTON A. SCOTT AND ALEXANDER G. HUG, OF CHICAGO, ILLINOIS, ASSIGNEES, BY MESNE ASSIGNMENTS, TO NATIONAL MANUFACTURING AND SPECIALTY COMPANY, OF CHICAGO, ILLINOIS, A CORPORATION OF ILLINOIS.

RAZOR-BLADE SHARPENER.

1,252,367.

Specification of Letters Patent.

Patented Jan. 1, 1918.

Application filed November 9, 1914. Serial No. 870,947.

To all whom it may concern:

Be it known that we, CLINTON A. SCOTT and ALEXANDER G. HUG, citizens of the United States, residing at the city of Chicago, in the county of Cook and State of Illinois, have invented certain new and useful Improvements in Razor-Blade Sharpeners, of which the following is a specification.

Our invention relates to devices for sharpening the blades of safety razors. As is well known the thick back of the ordinary razor blade forms a guide by which the angle or bevel of the edge, removed from the back by the concavity of the sides, is accurately gaged in the operation of honing or stropping. And the narrow extension or tang with the handle to which it is attached forms a means by which the blade can be held and turned from one side to the other on the sharpening element. But the blades of safety razors, consisting as they usually do of thin strips of steel sharpened on one or more edges, have no natural guide corresponding to the back of the ordinary razor blade, nor have they any means by which they may be held and manipulated in the process of fitting for use when dulled. One object of our invention is to afford means by which such blades may be securely held in proper relation to the sharpening element during the various steps of honing, stropping and setting for use. The blade when held thereby may readily be turned from side to side to alternate the strokes on opposite sides of the edge, and it is positively held at the proper angle to give the edges a uniform and correct bevel. And the predetermined angle is held during the stroke, no matter how careless or unskilled the operator. The invention also has for its objects the provision of means limiting the angle through which the pivoted blade holder may swing, so weighting or otherwise controlling the position of the blade holder that it will swing between the limits of movement provided for it, the employment of a roller structure or other means to define the angle at which the blade contacts with the sharpening element and which roller, when employed, is preferably of sufficient weight to swing the blade holder by gravity.

The invention has other features that will appear.

The principles of our invention are illustrated in the drawings, in which—

Figure 1 is a top view of our improved device, both top and bottom being, however, substantially the same;

Fig. 2 is a side view of the same in operative position;

Figs. 3, 4 and 5 show modifications of the device.

Further describing our invention with reference to the drawings, in which like characters of reference denote like parts throughout—1 is a blade holder having the jaws 2—2. A recessed portion 3 provides clearance for one part of a razor blade, while the front edges are closely brought together to receive the edge which is to be presented to the sharpening element. The said jaws may be made of two pieces of spring material brought closely together at the point 4, and there secured by screws or rivets 5. The pieces of which the blade holder sides are formed should be continued backwardly and so formed as to provide at 6 for the reception of a pin 7, which acts as a pivot upon which the blade holder may have limited pivotal movement, as hereinafter described. The axis of swinging movement afforded by the pivotal connection at 7 between the handle and the blade holder is normally substantially fixed with respect to the handle. The further rearward extension of said material to form the arms 8 provides mountings, at the ends of which may be journaled the wheel 9, mounted on the axle 10. The said wheel should be provided with a crowning 9', thereby permitting slight variations from side to side. Should the blade to be sharpened not be placed true in the jaws the slight rocking permitted by this form of the wheel permits the edge of the blade that is to be sharpened to lie true on the sharpening device. The wheel is preferably of such weight that it will overbalance the jaws and contents on the front side of the pivot 7. A handle 11 is extended to form the arms or bifurcations 12 at the ends of which, by means of the pin 7, the blade holding jaws are pivoted to the handle. Lugs 13 and 13'

on each side of the arms project inwardly therefrom and are adapted to engage the backwardly extended portions 8 of the blade holder and limit the pivotal action thereof to the space inclosed between said lugs. By this construction a connection is provided between the handle and blade holder that affords an axis of swinging movement for the blade holder which is normally substantially fixed with respect to the handle and which axis of movement is located with reference to the blade holder to have the blade edge that is to be sharpened disposed upon one side of said axis. The wheel constitutes the preferred form of roller structure to perform the function described for the wheel, this wheel also constituting an engaging means on the blade holder upon the other side of said axis from that upon which the blade edge being sharpened is disposed and extending laterally of the holder at each side thereof to be engageable with a sharpening element simultaneously with either side of the blade to define the angle of the blade to the sharpening element. This engaging means is also desirably weighted to turn the blade holder or carrier member by gravity, the weight being preferably mainly in the roller.

30 The device may be used in connection with a hone of any desired quality or other sharpening means, the upper face of which is indicated by the line 15-15 in Figs. 2, 3 and 5. A blade 16, which is to be sharpened, is slipped between the jaws 2, leaving the exposed edge 16'. The overweighted rearwardly extended portion of the holder causes the same to be tilted by gravity until the members 8 are in contact with the lower lugs 13 on the arms 12. The lower portion of the wheel 9 is thereby adapted to rest upon the upper face of the sharpening element and to positively gage the angle at which the edge 16' is applied thereto. After the operator has given one or more movements of the edge upon the hone or sharpening face, the device is reversed, when the overweighted rear portion drops until the members 8 are again in contact with lugs 13', whereby the face 50 of the wheel again rests on the sharpening element, causing the edge 16' of the blade to assume its proper angle. The reversals of the device may rapidly follow each other, the jaws automatically taking the proper angle with the sharpening face to impart the correct bevel to the blade held within them. The lugs 13, 13' constitute means for limiting the swinging movement of the holder with respect to the handle to an angle less than one hundred eighty degrees whereby the direction in which the blade that is being sharpened projects cannot be reversed as the device is moved from side to side.

A slightly modified form of the device is shown in Fig. 3, in which the blade holding jaws and the backward extension on the blade holder are formed in one piece and the extremities of the backwardly extended portion are off-set upwardly and downwardly to form bearing points 9'', there thus being formed another form of engaging means on the blade holder extending laterally of the holder at each side thereof to be engageable with a sharpening element simultaneously with either side of the blade and which will determine the angle of the blade holding jaws and take the place of the wheel 9, shown in the other figures. Such angle is determined by the vertical distance 17 from the point of contact to the extended portion of the jaws, or the extended portion thereof prolonged, and corresponds to the vertical radius of the wheel 9, when the device is used as above described. Weight may be added as 85 at 17' to overbalance the jaws.

A further modified form of the device is shown in Figs. 4 and 5, in which the jaws 2' and 2'' are pivoted together and to the arms 12 at 4'. A thumb screw 18 is threaded into the short arm 18' of the upper blade holding jaw 2''. The lower end of the screw bears upon the corresponding inner face of jaw 2' and causes such portions to be forced apart, thereby clamping the blade firmly within the jaws. The structure shown in Fig. 3 is also made the subject matter of a division of this application, the divisional application bearing Serial No. 203,941, filed Nov. 26, 1917.

Having thus fully described our invention what we claim as new and desire to secure by Letters Patent is—

1. In a device for sharpening razor blades; a handle, a plurality of arms spaced from each other and extending longitudinally therefrom, a blade holding member pivoted between the arms having jaws forwardly extended from the pivotal point and a portion extended rearwardly from the pivotal point, and a guiding device attached to and extended transversely in each direction from the rearwardly extended portion. 105 110

2. In a device for sharpening razor blades; a handle, a plurality of arms spaced from each other and extended longitudinally therefrom, a blade holding member pivoted between the arms having jaws forwardly extended from the pivotal point and a portion extended rearwardly from the pivotal point, a guide wheel axled on the rearwardly extended portion and adapted to overbalance the said jaws. 115 120

3. A safety razor blade sharpening holder consisting of a handle bearing two prongs, a blade-holding member pivoted between said prongs, means for limiting the movement of said blade-holding member between 125

said prongs, and a roller borne by said blade-holding member and adapted to roll on the surface of the strop or hone.

4. A safety razor blade sharpening holder 5 consisting of a handle bearing two prongs, lugs on said prongs adapted to limit the movement of the blade-holding member, a blade-holding member rotatably secured between said prongs, and bearing two leaves 10 adapted to receive and hold between them a safety razor blade, and a roller borne by said blade holding member and adapted to roll on the surface of the strop or hone.

5. In a device for sharpening razor 15 blades; a handle, a plurality of arms spaced from each other and extended longitudinally therefrom, a blade holding member pivoted between the arms having jaws forwardly extended from the pivotal point and a portion 20 extended rearwardly from the pivotal point, a guide wheel axled on the rearwardly extended portion adapted to overbalance the said jaws, and means for limiting the relative movement of the blade holding member 25 and the handle.

6. A device for holding a razor blade that is to be sharpened including a handle; a blade holder; a connection between the handle and blade holder affording an axis of 30 swinging movement for the blade holder which is normally substantially fixed with respect to the handle, and which axis of movement is located with reference to the blade holder to have the blade edge that is 35 to be sharpened disposed upon one side of said axis, and engaging means on the blade holder extending laterally of the holder at each side thereof on the other side of said axis to be engageable with a sharpening ele- 40 ment simultaneously with either side of the blade to define the angle of the blade to the sharpening element.

7. A device for holding a razor blade that is to be sharpened including a handle; a 45 blade holder; a connection between the handle and blade holder affording an axis of swinging movement for the blade holder which is normally substantially fixed with respect to the handle, and which axis of 50 movement is located with reference to the blade holder to have the blade edge that is to be sharpened disposed upon one side of said axis; and a roller structure on the blade holder upon the other side of said axis and 55 extending laterally of the holder at each side thereof to be engageable with a sharpening element simultaneously with either side of the blade to define the angle of the blade to the sharpening element.

60 8. A device for holding a razor blade that is to be sharpened including a handle; a blade holder; a connection between the handle and blade holder affording an axis of swinging movement for the blade holder

which is normally substantially fixed with 65 respect to the handle, and which axis of movement is located with reference to the blade holder to have the blade edge that is to be sharpened disposed upon one side of said axis; engaging means on the blade 70 holder extending laterally of the holder at each side thereof on the other side of said axis to be engageable with a sharpening element simultaneously with either side of the blade to define the angle of the blade to the 75 sharpening element, said means being sufficiently weighted to turn the holder by gravity; and means for limiting the swinging movement of the holder with reference to the handle to an angle less than one hundred 80 eighty degrees.

9. A device for holding a razor blade that is to be sharpened including a handle; a blade holder; a connection between the handle and blade holder affording an axis of 85 swinging movement for the blade holder which is normally substantially fixed with respect to the handle, and which axis of movement is located with reference to the blade holder to have the blade edge that is 90 to be sharpened disposed upon one side of said axis; engaging means on the blade holder extending laterally of the holder at each side thereof on the other side of said axis to be engageable with a sharpening ele- 95 ment simultaneously with either side of the blade to define the angle of the blade to the sharpening element; and means for limiting the swinging movement of the holder with reference to the handle to an angle less than 100 one hundred eighty degrees.

10. A device for holding a razor blade that is to be sharpened including a handle; a blade holder; a connection between the handle and blade holder affording an axis of 105 swinging movement for the blade holder which is normally substantially fixed with respect to the handle, and which axis of movement is located with reference to the blade holder to have the blade edge that is 110 to be sharpened disposed upon one side of said axis; a roller structure on the blade holder upon the other side of said axis and extending laterally of the holder at each side thereof to be engageable with a sharpening 115 element simultaneously with either side of the blade to define the angle of the blade to the sharpening element; and means for limiting the swinging movement of the holder with reference to the handle to an angle less than one hundred eighty degrees.

11. A device for holding a razor blade that is to be sharpened including a handle; a blade holder; a connection between the handle and blade holder affording an axis of 125 swinging movement for the blade holder which is normally substantially fixed with respect to the handle, and which axis of

movement is located with reference to the blade holder to have the blade edge that is to be sharpened disposed upon one side of said axis; and a roller carried by the blade holder, said roller having a crowning permitting slight rocking movement of the holder to enable the edge of the blade that is to be sharpened to lie true upon the sharpening element.

In witness whereof, we have hereunto subscribed our names, this 7th day of November, 1914, in the presence of two subscribing witnesses.
